ABSTRACT

An apparatus for tracking and indicating the status of a lock, comprising: a movement sensing device for sensing movement of a key related to said lock and providing information about said movement; a controller for reception of said information about said movement, processing said information and identifying a key rotation event that is associated with a lock status; and an indication unit being connected to said controller; providing an indication of the lock status according to control signals that are provided by said controller.

APPARATUS AND METHOD FOR ELECTRONIC LOCK KEY INDICATOR

RELATED APPLICATIONS

This application claims priority from provisional patent applications Ser. No. U.S. 61/279,969 filed on Oct. 29, 2009 titled Electronic Lock Indicator, and Ser. No. U.S. 61/335,202 filed on Jan. 4, 2010 titled Electronic Lock Key Indicator the disclosures of which are incorporated herein by reference.

BACKGROUND

The present invention relates to tracking the status of a lock in general, and to providing an indication of the status of a lock being either locked or unlocked, in particular.

Quite often, people forget whether they have locked the door in the house, office, or other premises, or not. As a common occurrence—someone may depart a building intending to secure it by externally locking a certain door using its corresponding key, upon departure. However, following his departure, he or she may be unable to recall whether or not they have actually locked the door, securing it by turning the corresponding key into a locked position. Hence, there is a need to provide a reliable, low-cost, convenient device which may be attached to the majority of portable keys, which device shall clearly indicate whether the lock corresponding to said key has been actuated into the lock position or not.

Several inventors have suggested various devices including attachments to standard keys, which would hopefully indicate the most recent lock position. However, most of these inventions rely on the user exerting a force on the attachment housing, using his fingers while turning the key in the clockwise or counter-clockwise direction. This force, or rotational torque, has been suggested to activate an array of mechanical and/or electronic switching devices which in turn were conceived as leading to the sought after locked indication. (See, for example, U.S. Pat. No. 4,440,011 by Klein, and/or US Patent Application 20090201151 of 13 Aug. 2009 by Yosef De Levie et al.) Certain inventions even indicated a specific location on said attachment in which the user's thumb and/or finger were to be positioned. Many keys are inserted into the lock in a horizontal position i.e. the key head is parallel to the floor, such that a thumb-activated switch may be difficult to achieve. Furthermore, occasional contact of keys including said attachments with various external objects, e.g.—coins or other objects in a user pockets, may reset the memory/indicator into an erroneous position. Moreover, several users may have different physiological structures of hands and fingers resulting in a great variety of forces being applied to the key while rotated inside the lock, which may lead to errors in the indicator output.

BRIEF SUMMARY

The present invention introduces an electronic device and system, included within a housing that can be attached to most of the known keys, providing an indication of the most recent status of the lock corresponding to said key. Said device shall indicate whether the lock was left locked or unlocked. According to the teachings of this invention, when the user inserts the key into the lock and rotates the key about its longitudinal axis in a clockwise (CW) or counterclockwise (CCW) direction, which rotation causes the lock to correspondingly unlock or lock, the attached device shall sense the direction of rotation of the key, thus indicating whether the

lock was left in an unlocked or locked position. Sensing of the direction of rotation of the key is achieved independently of the user's positioning of his fingers and/or hand, and does not depend on users' fingers pressure during the rotation of the key and the attached device. Moreover, there is no need to use magnets and/or mechanical devices. In other words, the particular manner which caused the rotation of the key and the particular positioning of the user's thumb and/or fingers on the attached housing of this invention are substantially inconsequential insofar as the core of this invention is concerned. According to the teachings of this invention, the indication of the direction of rotation of the key is achieved by means of electronic sensing using transducers that issue electronic signals the detection of which uniquely indicates a clockwise (CW) or counterclockwise (CCW) rotation of the key about its longitudinal axis, independently of how said housing is being held by the user. In one embodiment, said transducer may be an accelerometer or more specifically an integrated-circuit accelerometer. The relative small-size (few millimeters) integrated circuit accelerometer available today, referred to as ICA, can be mounted inside the housing of the device attached to the key, connected to a power-source such as a battery, and an electronic controller the output of which is fed into one or more electronic indicators which indicate the most recent status of the corresponding lock, i.e. whether it was left in locked or unlocked position. These ICA devices consist of a capacitive sensing g-cell consisting of an X-Y and a Z cell all within a single package, which is sealed hermetically at the wafer level. The g-cell is the sensing element of the system which consists of polysilicon mechanical structures. Acceleration is detected when a displacement in X, Y, or Z is detected in the g-cells. The displacement creates a change in capacitance. The ICA uses a switched capacitor technique to measure the g-cell capacitors and the acceleration and related rotational data is extracted from a difference in the capacitance. The ICA provides signal conditioning and filtering to convert the capacitance into a high level output voltage which is ratiometric and proportional to the rotation of the key. The g-cells are combined with the signal conditioning ICA in a single integrated circuit package.

As will be detailed below, the ICA can be mounted inside the housing such that one of its three Axes is parallel to the longitudinal axis of the key, for example the Y axis. The electronic output signals corresponding to the movement of the other two axes X and Z in this case, can be detected and processed resulting in a clear indication of the door-lock status.

In some embodiments of the disclosed subject matter there is provided an apparatus for tracking and indicating the status of a lock, comprising: a movement sensing device for sensing movement of a key related to said lock and providing information about said movement; a controller for reception of said information about said movement, processing said information and identifying a key rotation event that is associated with a lock status; and an indication unit being connected to said controller; providing an indication of the lock status according to control signals that are provided by said controller.

In some embodiments of the disclosed subject matter the apparatus is attached to the key.

In some embodiments of the disclosed subject matter the movement sensing device senses spatial movement.

In some embodiments of the disclosed subject matter the movement sensing device comprises a motion sensor that provide said information about the spatial movement of the key with reference to three spatial axis X,Y,Z.

In some embodiments of the disclosed subject matter the motion sensor is a three axis motion sensor.

In some embodiments of the disclosed subject matter the motion sensor is an accelerometer.

In some embodiments of the disclosed subject matter the accelerometer having a three axis detection capability.

In some embodiments of the disclosed subject matter the apparatus further includes a micro-switch that is attached to the key and provides the indication that the key was inserted into the lock.

In some embodiments of the disclosed subject matter the micro-switch controls the power state of the apparatus, enabling to activate the apparatus only when a micro switch indicates an inserted key state.

In some embodiments of the disclosed subject matter the controller identifies the key rotation event by processing voltage signals from the movement sensing device, said voltage signals reflect movement information related to two axes that are perpendicular to axis that is defined by a key insertion direction.

In some embodiments of the disclosed subject matter the controller identifies the key rotation event only when there is the indication of an inserted key, wherein an inserted key indication is provided by a micro switch that is attached to a key housing or by processing voltage signals from the movement sensing device, said voltage signals reflect movement information related to movement in a direction that is parallel to the ground.

In some embodiments of the disclosed subject matter the controller identifies a key insertion event according to a motion parallel to longitudinal axis due to protrusions that are formed on the key.

In some embodiments of the disclosed subject matter identifying a key insertion is further conditioned on detection of movements in X or Z direction

In some embodiments of the disclosed subject matter associating the key rotation event with the lock status is responsive to the lock orientation as a left oriented lock or right oriented lock.

In some embodiments of the disclosed subject matter identifying the key rotation event is responsive to a lock type being either vertical or horizontal.

In some embodiments of the disclosed subject matter identifying the key rotation event is determined by voltage levels that are provided by the movement sensing device, compared to predetermined thresholds.

In some embodiments of the disclosed subject matter identifying the status of said lock related to the key is determined by identifying a unique sequence of digital pulses that result from comparison of the voltage levels that are provided by the movement sensing device to the predetermined thresholds.

In some embodiments of the disclosed subject matter there is provided a method for tracking and indicating the status of a lock, comprising attaching a movement sensing device to a key that is used for open or close said lock; processing information that is provided by said movement sensing device and identifying a key rotation event that is associated with a lock status; and providing an indication of the lock status according to control signals that are provided by said processing of the information that is provided by said movement sensing device.

In some embodiments of the disclosed subject matter the movement sensing device is an accelerometer.

THE BRIEF DESCRIPTION OF THE SEVERAL VIEWS OF THE DRAWINGS

The present disclosed subject matter will be understood and appreciated more fully from the following detailed

description taken in conjunction with the drawings in which corresponding or like numerals or characters indicate corresponding or like components. Unless indicated otherwise, the drawings provide exemplary embodiments or aspects of the disclosure and do not limit the scope of the disclosure. In the drawings:

FIG. 1A illustrates a standard key inserted in a portable housing which includes the major electronic constituent components necessary for the implementation of this invention.

FIG. 1B illustrates yet another standard key inserted in the portable housing indicating the layout of the electronic components within the attached housing.

FIG. 1C shows yet another configuration deploying an additional external housing connected to the Key Head.

FIG. 2A illustrates the general relationship between the movement of the key and the electronic transducer deployed in this invention with reference to one axis (Prior Art).

FIG. 2B illustrates the relationship between the magnitude of the electronic output signal of the transducer and the angle of rotation of the key with reference to one axis.

FIG. 3 is a block diagram of the electronic components and the interconnections between them according to one embodiment in accordance with the disclosed subject matter.

FIG. 4A shows the output electronic signals corresponding to a clockwise rotation about the longitudinal axis of the key.

FIG. 4B shows the output electronic signals corresponding to a counter-clockwise rotation about the longitudinal axis of the key.

FIG. 4C illustrates the spatial orientation of a key, its longitudinal axis relative to the two other spatial axes and the rotational directions within this framework.

FIG. 5 illustrates the analog signals generated by the Accelerometer for a 360 degrees rotation of Keys and corresponding binary signals in accordance with the disclosed subject matter.

FIG. 6 presents an algorithm based on derivative detection and illustrating the overall logical flow of information and decision points in one embodiment accordance with the disclosed subject matter.

FIG. 7 depicts a general block diagram of the lock key indicator apparatus in accordance with the disclosed subject matter.

DETAILED DESCRIPTION

All technical terms used herein have the same meaning as commonly understood by one skilled in the art pertaining to the invention and in the art of electronics.

The disclosed subject matter is described below with reference to flowchart illustrations and/or block diagrams of methods, apparatus (systems) and computer program products according to embodiments of the subject matter. It will be understood that each block of the flowchart illustrations and/or block diagrams, and combinations of blocks in the flowchart illustrations and/or block diagrams, can be implemented by computer program instructions. These computer program instructions may be provided to a processor of a general purpose computer, special purpose computer, digital controller, or other programmable data processing apparatus to produce a machine, such that the instructions, which execute via the processor of the computer or other programmable data processing apparatus, create means for implementing the functions/acts specified in the flowchart and/or block diagram block or blocks.

Referring now to FIGS. 1-7 in greater detail, FIG. 1 shows a key 101 having a head or handle 103 which head or handle is inserted into, or otherwise being attached to a key housing

150 such that the portion of the key to be inserted into the lock extends out of said housing. The electronic components used in this disclosure are included and interconnected among themselves within the housing 150 which can be mounted onto, or integrated within the key head, or attached to almost any type of key for indicating the most recent lock or unlock status of the lock operable by the key, by indicating the last direction of rotation about the key's longitudinal axis. FIG. 1A shows the housing 150 attached to one type of key 101, whereas another type of key 101b is depicted in FIG. 1B whose head is inserted in a similar housing; FIG. 1C shows an alternative housing 151 attached externally to the standard key-head. The housing 150 or alternative housing 151 may be manufactured using several well-known techniques such as injection molding techniques using various plastic materials.

FIG. 1A shows a movement sensing device 105 that is capable of detecting a motion in three dimensions. The movement sensing device 105 can be a sensor such as an accelerometer unit. The movement sensing device 105 may be a relative small-size (few millimeters) integrated circuit accelerometer (ICA). In one embodiment in accordance with the disclosed subject matter the movement sensing device output is an analog output and it is routed to a an analog to digital (ADC) unit 108. The analog to digital (ADC) unit 108 output is connected to a digital electronic controller (hereinafter "controller") 106 that is processing the signals that are provided by the ADC and defines the lock's status, according to the key's 101 last rotation, either open or locked. Controller 106 controls indication unit 107 that provides a visual indication of the lock's status. Controller 106 can also be a micro-processor.

In an exemplary embodiment a green LED light indicates a locked status while a red LED light indicates an unlocked status. A battery 104 provides power supply to the abovementioned components.

In another embodiment in accordance with the disclosed subject matter, power supply from battery 104 is conditioned by power-save switch 130 that enables to save battery 104 power when either detection or indication may be suspended.

An alternate configuration is shown in FIG. 1C. Here, movement sensing device 105 is attached directly to a standard key-head or alternative housing 151, which is attached by rings (or any other connecting mechanism) 154 to an external housing 152 including the rest of the electronic components (such as analog to digital (ADC) unit 108, controller 106 etc.) described below in more detail. A compact cable, 153, carrying the electronic signals from movement sensing device 105 to the rest of the electronics as well as a connection to battery 104, is shown.

It should be noted that the present disclosure is not limited to any specific structure and connection scheme. FIGS. 1A, 1B and 1C are given by a way of a non-limiting example; actually the only physical constraint is that movement sensor device 105 must be physically attached to key 101 in order to enable the tracking of key 101 movements. It should further be noted that while the embodiments that are shown in FIGS. 1A-1C describe a specific structure/architecture, the same functionality may be achieved with alternative structure/architecture. For example movement sensing device 105 may be an integrated unit that includes also the functionality of analog unit 108. (The output of movement sensor device 105 provides digital signals directly to controller 106).

It should be further noted that movement sensing device 105 is a generic name that should be construed as any device that is adapted to provide information about a component that it is attached to, whether it is based on acceleration, motion,

speed, placement or any information that enables to track the component motion. E.g. a gyroscope.

The direction of rotation of the key relative to the spatial orientation of the key and its related lock is indicated in all figures as follows: The longitudinal axis of the key, along which it is inserted into the lock, is defined herein as the Y axis, marked 110. A clockwise (CW) rotation of the key around its Y axis, looking in the direction of the arrow marked on Y, is marked 112, whereas a counter-clockwise rotation (CCW) of the same key is marked 111. The lock may be positioned within the X-Z plane which is usually perpendicular to the Y axis, with the Z axis, 132 (FIG. 4C), pointing up, perpendicular to Y, and the X axis, 131 (FIG. 4C), pointing into the plane of the paper on which the various figures are drawn and the X axis, 131, pointing into the plane of the paper on which FIGS. 1A,1B and 1C are drawn.

In an exemplary embodiment When the user inserts the key 101 into the lock and rotates the key 101 about its longitudinal axis in a clockwise (CW), 112, or counterclockwise (CCW), 111, direction, which rotation causes the lock to correspondingly unlock or lock, the movement sensing device 105 (movement sensing device) attached to the key shall sense the direction of rotation (either CCW 111 or CW 112) of the key 101, thus indicating whether the lock was left in an unlocked or locked position (taking into account the kind of lock, either a right or a left oriented lock).

Sensing of the direction of rotation of the key is achieved independently of the users positioning of his fingers and/or hand, and does not depend on users' fingers pressure on any switches or specific regions located on the attached device. Moreover, in order to sense the rotation of key 101, there is no need to use magnets and/or mechanical levers and/or switches. The particular manner that caused the rotation of the key and the particular positioning of the user's thumb and/or fingers on the attached housing of the tracking device according to the disclosed subject matter are substantially inconsequential insofar as the core of the disclosed subject matter is concerned.

According to the teachings of this disclosure, the indication 40 of the direction of rotation of the key is achieved by means of electronic sensing using transducers and related electronic circuits that issue electronic signals the detection of which uniquely indicates a clockwise (CW), 112, or counterclockwise (CCW), 111, rotation of the key about its longitudinal axis, 110, independently of how said housing is being physically held by the user.

In one embodiment, said transducer may be a movement sensing device, 105, or more specifically an integrated-circuit accelerometer. The movement sensing device 105, available 50 today, such as analog accelerometer Model number 7360 or digital accelerometer model 7361 manufactured by Freescale Corp, referred to as ICA, can be mounted inside the housing, 150, of the device attached to the key, 101, connected to a power-source such as a battery, 104, and electronic analog 55 circuits including analog to digital (ADC) unit 108, feeding an electronic controller 106, which includes a memory, the output of which is fed into one or more electronic indicators, (indication unit) 107, which when activated, indicates the most recent status of the corresponding lock, i.e. whether it 60 was left in locked or unlocked position. The movement sensing device 105, may consist of a capacitive sensing g-cell consisting of X-Y and a Z cells all within a single package, which is sealed hermetically at the wafer level. The g-cell is the sensing element of the system, which may consist of polysilicon mechanical structures. Acceleration is detected when a displacement in X, 131, Y, 110, or Z, 132, (FIG. 40) is 65 detected in the g-cells. The displacement creates a change in

capacitance. The ICA uses a switched capacitor technique to measure the g-cell capacitors thus the acceleration and related rotational data is extracted from a difference in the capacitance. As known in the professional literature, the g-cell is a mechanical structure formed from semiconductor materials (polysilicon) using semiconductor manufacturing processes.

In reference to FIG. 2A, it can be modeled as a set of beams, 215 and 217, positioned in proximity to a movable central mass, 216, that moves between beams 215, 217. The movable beam is deflected from its rest position when the apparatus is subjected to acceleration. As the beams are attached to the central mass move, the distance from them to the fixed beams 215, 217 on one side will increase by the same amount that the distance to the fixed beams 215, 217 on the other side decreases. The change in distance that is translated to a change in capacitance is a measure of acceleration. The g-cell beams form two back-to-back capacitors 213 and 214 (shown in FIG. 2A). As the center beam moves with acceleration, the distance between the beams changes and each capacitor's value will change following the equation $C = A \in / D$, where A is the area of the beam, $\in$ is the dielectric constant, and D is the distance between the beams.

The movement sensing device 105 uses switched capacitor techniques to measure the g-cell capacitors and extract the acceleration data from the difference between the two capacitors, which are converted by the movement sensing device into a detectable voltage that is proportional to the acceleration. In one embodiment in accordance with the present disclosure, if a movement sensing device 105, is attached to key 101 as illustrated, the output voltage along certain axis is proportional to a rotation (which causes acceleration) as depicted in FIG. 2B, in which the magnitude of the output voltage, 222, along a certain axis shown as output voltage signal 439 (shown in FIGS. 4A and 4B), will increase as the Angle of rotation, 221, increases, while said output voltage will decrease as the Angle of rotation decreases.

FIG. 3 is a block diagram of the electronic components and the interconnections between them according to one embodiment in accordance with the disclosed subject matter. FIG. 3 shows the electronic components, corresponding to the ones shown packaged within housing 150 in FIG. 1, as they are generally interconnected so as to process the signals to result in a lock or unlock indication on indication unit 107. The movement sensing device 105, is feeding output signals 324, 325 and 326, corresponding to the X, Y and Z axes. In an exemplary embodiment, these signals are fed into corresponding analog circuit unit, analog to digital (ADC) unit 108, which include comparator circuits with threshold detectors (or differentiators), which output the corresponding voltage signals and feeds these signals to corresponding input 327, 328, 329 of controller (processor) 106. Said controller 106 processes the digital signals and makes the decisions regarding the lock's status and provides the appropriate controls to indication unit 107.

In an exemplary embodiment in accordance with the disclosed subject matter. The movement sensing device 105, as well as controller 106, will be in its "sleep mode", in which they will draw minimum current from battery 104. Such sleep mode occurs when power-save switch 130 is open and in this state movement sensing device is powered by V_s (standby voltage) 352 and the same voltage powers also controller 106 (351). Standby voltage is at a level that enables key insertion detection by micro switch 136 and optionally additional limited activities. When power-save switch 130 is closed by the user, or activated by micro switch 136 upon insertion of the key into the lock if mounted on the key (or the key housing 150) as shown, movement sensing device 105 will respond to

the insertion and rotation of the key feeding signals (marked as 437, 438, and 439 in FIGS. 4A and 4B) into analog circuit unit—analog unit 108. It should be noted that analog unit 108, which includes at its output an Analog to Digital Converter 5 may be included within the movement sensing device 105, (marked optionally as 382), (there are commercially available digital accelerometers whose output is already in digital format) so it can be fed directly into the controller 106.

It should be noted that micro-switch 136 is optional and the 10 present disclosure is not limited to any embodiment that includes micro-switch 136 since a key insertion can also be detected as described in FIG. 4 by sensing signal 438.

FIG. 3 further shows switch 373 which may comprise multiple functions. In one embodiment switch 373 may 15 switch on/off battery power, either full power connect/disconnect or it may enable partial switching for example for standby/sleep mode power state. Switch 373 may be used for activating/deactivating indication unit 107. Switch 373 may also be used to initially program controller 106 to operate in 20 a "left door" or "right door" mode. Switch 373 may further be used for manually providing a "key inserted" indication. The functionality of switch 373 may be programmed by the user as is offered by commercially existing switches.

In accordance with the example and spatial orientation 25 depicted in FIG. 4A, when there is a signal, 441, indicating the insertion of a key, present on its input 328 controller 106 proceeds to look/wait for signals fed into its inputs 327 and 329. Upon detection of such signals, controller 106 will 30 proceed to determine, based on the output of analog unit 108, if a CW 112, or CCW 111 rotation of the key was performed. Analog unit 108 may perform a comparison of the signals with threshold levels that are described hereinafter (with reference to FIG. 6) or by differentiation on its input signals, i.e. take the time derivative of the voltage signal— dv/dt —such 35 that in case of a CW, 112, rotation it will feed a positive pulse into the controller, while in case of a CCW, 111, rotation it will feed a negative pulse into the controller at its input 329. Accordingly, controller 106 will perform an (Analog to Digital) ND conversion on these signals, process and store this 40 information in its memory. Upon inquiry by a user enabling power-save switch 130, the controller 106 issues an enable or disable command, via its terminal 344, to indication unit 107, which may be a LED (Light Emitting Diode), or similar 45 device, so that indication unit 107 will either light up or stay disabled, indicating a locked or unlocked status of the lock respectively.

It should be noted that the present disclosure is not limited to an implementation that utilizes a power-save micro-switch. Thus, controller 106 may be waiting for key rotation indication 50 continuously.

In an exemplary embodiment according to the disclosed subject matter, the primary sensing of rotation of the key which is the fundamental mechanism used in this invention to indicate the lock or unlock status of the lock, is based on the 55 output voltage of an accelerometer (Actually the movement sensing device 105 includes 3 units, for spatial movement sensing in three axes) which is proportional to said rotation.

FIG. 4A depicts the initial shape of the output voltages of the three axes, measured on an Oscilloscope in case of a CW 60 rotation, following the insertion of a key into its corresponding lock, subsequently locking or unlocking the lock. In case of CW 112 rotation, initial output voltage signals 437, 438, 439 correspond to x-axis 131, y-axis 110, and z-axis 132 respectively, as illustrated on FIG. 4A and FIG. 4C. Output 65 sensing signals can also be termed as sensing signals. In case of a COW rotation 111, FIG. 4B illustrates initial output voltage signals 437, 438, 439 correspond again to axis 131,

110, and 132 respectively, the spatial orientation of key, 101 relative to the above axes is depicted in FIG. 4c.

With reference to FIG. 4A and FIG. 4B signal 441 appearing on axis corresponding to sensing signal 438 as the key is inserted into the lock, irrespective of whether said insertion was followed by a CW, 112, or CCW, 111, rotation. This signal—identifying the insertion (or removal) of the key into the lock will be used, as explained later, to prevent false indications of lock status as well as to conserve Battery 4, energy. Comparing voltage signal 437 following the CW, 112, vs. the CCW, 111, rotation we note that in both cases the voltage was decreased from a higher level to a lower level. However, comparing output voltage signals 439 (the Z axis), there is a significant change in behavior: In case of a CW rotation, 112,—the voltage at 439 is increased following the initial rotation, while in the case of CCW, 111, rotation, the voltage is decreased. Hence, this disclosure introduces a unique method to distinguish between a locking and an unlocking operation of a key by means of sensing the output voltages of an electronic accelerometer, relying on the behavior described above: Sensing of two distinctly different output voltages—one increasing with CW rotation, vs. the other decreasing with CCW rotation of the key can be used as a means to sense and subsequently memorize and indicate the locked or unlocked status of the lock to which the key corresponds.

It should be noted that FIGS. 4A and 4B describe one embodiment that is associated with a movement sensing device 105. However, when another type of movement sensing device 105 is used than the specific behavior of sensing signal 437, 438, 439 (hereinafter “signals signature”) may be different but there will still provide a signal signature that enables to differentiate between a CW rotation and a CCW rotation.

FIG. 5 illustrates the analog signals generated by the Accelerometer for a 360 degrees rotation of Keys and corresponding binary signals.

Two different key (actually dictated only by the lock orientation) orientations are depicted in FIG. 5. While in both cases the Y axis, 110, or the longitudinal Key axis is the same, the first case “Horizontal Key”, is oriented with its X-Y, 131-110, plane parallel to the ground, while in the second case “Vertical Key”, has its Y-Z, 110-132, plane perpendicular to the ground. Output signals of Accelerometer, 105, corresponding to key-rotations are portrayed as Vin for both the X, 131, and Z, 132, axes for complete full turns (360 degrees) in both the CW, 112, and CCW, 111, directions.

FIG. 5 describes all the four combinations of Horizontal/vertical key and CW/CCW, each one of the four combinations is described by six graphs: V in along X axis, Vin along Z axis—the voltages following digitization being provided by the accelerometer are marked: V_{XL} , V_{XH} , V_{ZL} and V_{ZH} . While the methodology is equal for all four cases, the present description refers to CW Horizontal Key only.

When an horizontal key 520 is turned CW 525 the voltage Vin (along X axis) 501 that is provided by accelerometer 105 for the X axis is first increased and then decreases, reaching a minimum and returning to its original level (reference level). Vin 501 is compared to two threshold levels VTH_H (Threshold High) 505 and VTH_L (Threshold Low) 607. The comparison provides two digital signals— V_{XL} 510 and V_{XH} 515, wherein V_{XL} is high whenever Vin (ALONG x AXIS) is below VTH_L and V_{XH} is high whenever Vin is greater than VTH_H . The same applies for Z axis wherein Vin is marked 570, V_{ZL} 572 and V_{ZH} 574.

While the graphs that are shown in FIG. 5 describe empirical behavior of the voltages that are provided in all four cases

(Horizontal CW 525, Horizontal CCW 526, Vertical CW 527 and vertical CCW 528), each of the four cases results with a unique sequence of zeros/tow and ones/high (The uniqueness is achieved off course, if reference is made to the combination all four signals V_{XL} , V_{XH} , V_{ZL} , V_{ZH} as each pair alone is not unique). It could be readily appreciated by a person skilled in the art that a simple processing of V_{XL} , V_{XH} , V_{ZL} and V_{ZH} enables to uniquely identify CW or CCW rotation of a key in either a horizontal or vertical key scenario. Each of the four cases: Horizontal key CW or CCW rotation and Vertical key CW or CCW rotation results with a unique pattern/sequence that is clearly distinguishable from other cases.

In a case of using a digital accelerometer, the output of said accelerometer is already in digital form and can be fed directly to the controller 106 for further processing, based on the criteria described above. E.g. the threshold voltage levels (VTH_H , VTH_L) can be programmed into the digital controller 106, and digitally compared to the digitized Vin signals.

An exemplary detection and lock-status—indication flow is described in a flowchart depicted in FIG. 6.

Upon apparatus reception (603) the user should configure the apparatus to either “Right Lock” or “Left Lock” according to the actual lock position (604). This setting is required because CW 112 key rotation locks a “Right Lock” door and unlocks a “Left Lock” door. (“Right Lock”/“Left Lock” is defined from the outside/outdoor side). The apparatus is now in an IDLE state (605) where in an exemplary embodiment it is activated by pressing a switch 373 (607). It should be noted that in other embodiments in accordance with the disclosed subject matter, the apparatus may be continuously active or activated by default wherein a switch pressing will move the apparatus from active state to IDLE state. However, while battery power is usually limited (due to the nature of the apparatus there is a need to limit battery size), it is expected to use means for reducing power consumption at least when the apparatus is not expected to be functioning for relatively long periods. Pressing the double-sided switch moves the apparatus to active state (615). In the active state the apparatus is programmed to detect a key insertion or removal (616). As shown in FIG. 4 the signal marked as 441 is an example of insertion/removal detection.

If in the active state (615) there is no indication on key insertion within a predetermined time-interval the apparatus disables all circuits and moves to IDLE state (617). If a key insertion is detected the apparatus opens a waiting period of a predetermined length of time (618) to check the signals condition in all three axis (620). If there is no positive indication on key rotation within a predetermined length of time (618) the apparatus returns to the IDLE state.

Positive indications on key rotation may result with CW rotation 112 (631) or CCW 111 rotation (630) depending on signals analysis. As was previously described with reference to FIG. 5, the signal that are provided by movement sensing device 105 reflect the movements of the key 101 relative to axes X and Z. Control unit 106 is adapted to identify CW or CCW rotation according to signal levels compared to the thresholds 626. Alternatively the signals from movement sensing device 105 can be analyzed by a differentiators circuit that checks dX/dt and dZ/dt (wherein X and Z are the voltage levels that are received from accelerometer 105).

A XOR (632) check is performed to eliminate false detection or proceed with CW or CCW key rotation (633). (If both CW rotation and CCW rotation are detected it definitely means a false detection occurrence) when a false detection occurs the apparatus returns to wait for signal condition check or to wait for insertion or removal state (616), depending on if it is still within a predefined period (618).

11

If a valid CW is detected (635) or a valid CCW (634) is detected then the apparatus needs to translate the rotation according to the Left/Right door setting (636, 637). The result may be one of four cases: Left door open (640), Left door closed (641), Right door open (643) Right door closed (642). The result is stored in the apparatus memory (that is part of controller 106). The apparatus then waits for a predetermined time-interval (645) to look for an additional rotation. An additional rotation may be a second rotation similar to the just-identified rotation, in case that a lock can rotate twice, and it can be an opposite action, i.e. in case that a lock is opened right after being closed or vice versa—being locked right after being opened. If a lock can be rotated twice (or more) for double locking, it is also important to receive accurate indication about the amount of CW or CCW rotations, e.g. one CW rotation does not unlock a lock that was locked by two CCW rotations. After the data is stored in the apparatus memory 647 the apparatus goes back to IDLE state.

At any moment the user may press twice the double sided switches (608) and the current lock status (609) will be displayed by a colored LED indication door locked (610) green LED, door unlocked (611) red LED, or when the indication unit 107 is IDLE the LED may be turned off (612).

Obviously, FIG. 6 describes one of many possible flows in accordance with the present disclosure. For example the indication unit may be designed in many other manners, the apparatus may not implement any power-save modes, thus—being continuously activated.

FIG. 7 depicts a general block diagram of the lock key indicator apparatus in accordance with the disclosed subject matter.

FIG. 7 shows the output signals 724, 725 and 726, (corresponding to X, Y and Z axes respectively) of the Accelerometer (movement sensing unit) 105, fed into the Analog circuits, analog unit 108, which in turn feed the generated binary signals, 766, 767, 768, 769 and 770 into controller 106. Controller 106 may be implemented by a CPLD (Complex Programmable Logic Device), an FPGA, digital controller, or any other digital microprocessor. Said controller is initially set to a left or right door/lock by switch 781. The output of controller 106 will cause Red light-indicator, 783, to indicate an unlocked position, or a Green light-indicator, 784, to indicate a Locked position. As previously mentioned, analog unit 108 may be integrated within movement sensing unit 105, wherein in this case the outputs of movement sensing unit 105 are three digital signals

It should be appreciated that the above described methods and apparatuses may be varied in many ways, including omitting or adding steps, changing the order of steps and the type of devices used. It should be appreciated that different features may be combined in different ways. In particular, not all the features shown above in a particular embodiment are necessary in every embodiment of the disclosed subject matter. Further combinations of the above features are also considered to be within the scope of some embodiments of the disclosed subject matter.

Section headings are provided for assistance in navigation and should not be considered as necessarily limiting the contents of the section.

It will be appreciated by persons skilled in the art that the present disclosure is not limited to what has been particularly shown and described hereinabove. Rather the scope of the present disclosure is defined only by the claims, which follow.

The invention claimed is:

1. An apparatus for tracking and indicating the status of a lock, comprising:

12

(a) an at least three axis motion sensor that senses spatial movement and provides motion movement information about said spatial movement of a key with reference to three spatial axes for sensing movement of the key relative to said lock and providing movement information about said movement, wherein said movement information enables, a continuous tracking of the complete path of motion including the insertion, removal and rotation movements of the key in the lock and determining the direction of rotation of the key relative to the lock;

(b) a controller for reception of said movements information about said movements, wherein said controller is configured to processing said information and identifying the direction of the insertion, removal and rotation movements of the key that are associated with the status of the lock, wherein the controller identifies the key rotation event by processing voltage signals from the motion sensor, said voltage signals reflect movement information relative to two axes that are perpendicular to axis that is defined by a key insertion direction;

(c) an indication unit connected to said controller; providing an indication of the lock status according to control signals that are provided by said controller; and wherein said apparatus is attached to the key.

2. The apparatus according to claim 1, wherein the motion sensor is an accelerometer.

3. The apparatus according to claim 2, wherein the motion sensor is the accelerometer having a three axis detection capability.

4. The apparatus according to claim 1, wherein the apparatus further includes a switch enabling to program said controller.

5. The apparatus according to claim 4, wherein the switch controls the power state of the apparatus.

6. The apparatus according to claim 1, wherein the controller identifies the key rotation event only when there is the indication of an inserted key, wherein an inserted key indication is provided by processing voltage signals from the movement sensing device, said voltage signals reflect movement information related to movement in a direction that is parallel to the direction of insertion of the key.

7. The apparatus according to claim 1, wherein the controller identifies a key insertion event according to a motion parallel to longitudinal axis of the key due to protrusions that are formed on the key.

8. The apparatus according to claim 5, wherein identifying a key insertion is further conditioned on detection of movements in X or Z direction.

9. The apparatus according to claim 1, wherein associating the key rotation event with the lock status is responsive to the lock orientation as a left oriented lock or right oriented lock.

10. The apparatus according to claim 1, wherein identifying the key rotation event is responsive to a lock type being either vertical or horizontal.

11. The apparatus according to claim 1, wherein identifying the key rotation event is determined by voltage levels that are provided by the movement sensing device, compared to predetermined thresholds.

12. The apparatus and system according to claim 11 wherein identifying the status of said lock related to the key is determined by identifying a unique sequence of digital pulses that result from comparison of the voltage levels that are provided by the movement sensing device to the predetermined thresholds.

13. A method for tracking and indicating the status of a lock, comprising

13

- (a) attaching a to a key that is used for opening or closing said lock a three axis motion sensor that senses spatial movement and provides motion movement information about said spatial movement of the key with reference to three spatial axes X, Y and Z;
- (b) continuously tracking the complete path of motion including insertion, removal and rotation movements of the key in the lock with said movement sensing device, and providing movement information regarding said movements;
- (c) processing the movement information that is provided by said movement sensing device;
- (d) identifying the direction of insertion and removal and rotation movements of the key in the lock based on said

5

10

14

movement information, wherein the key rotation event is identified by processing voltage signals from the motion sensor, said voltage signals reflect movement information relative to two axes that are perpendicular to axis that is defined by a key insertion direction; and

- (e) providing an indication of the lock status according to control signals that are provided by said processing of the movement information that is provided by said movement sensing device.

14. The method according to claim **13**, wherein the movement sensing device is an accelerometer.
